DESIGN FOR AN ELECTRICAL DRAFTSMAN'S SYMBOL TEMPLATE

Edward A. Pullan, Los Angeles, Calif.

Application August 7, 1942, Serial No. 107,846

Term of patent 7 years

To all whom it may concern:

Be it known that I, Edward A. Pullan, a citizen of the United States, residing at Los Angeles, in the county of Los Angeles and State of California, have invented a new, original, and ornamental Design for an Electrical Draftsman's Symbol Template, of which the following is a specification, reference being had to the accompanying drawing, forming part thereof.

Fig. 1 is a top plan view of a template showing my new design.

Fig. 2 is a sectional view on line 2—2 of Fig. 1 looking in the direction of the arrows.

I claim:

The ornamental design for an electrical draftsman's symbol template, as shown.

EDWARD A. PULLAN.
